Patented Aug. 2, 1927.

UNITED STATES PATENT OFFICE.

WALTER L. CHAPLIN, OF SYRACUSE, NEW YORK, ASSIGNOR TO THE SMITH-LEE COMPANY, OF ONEIDA, NEW YORK, A PARTNERSHIP COMPOSED OF WILBERT L. SMITH, HURLBUT W. SMITH, AND ESTATE OF M. C. SMITH.

BOTTLE CAP.

Application filed July 24, 1924. Serial No. 728,030.

This invention relates to closures for bottles and jars and particularly for milk bottles. Closures for this purpose have usually been made of paper board in the form of disks adapted to fit closely in a groove at the top or in the neck of the bottle. The present invention is an improvement upon that type of bottle cap or closure which is provided with a tab cut from the body of the material, the cut extending part way but not altogether through the material. The main object of the invention is to provide a bottle cap or closure of this character having a section which may be raised to permit of partially emptying the bottle or of inserting a straw without removing the main portion of the cap from its seat in the bottle neck.

In patented structures disk-like bottle caps have been provided with creases of various characters to permit one portion to hinge upon the other, the creases usually extending from edge to edge of the cap, the creases being formed either in the upper or lower surface. In connection with a cap of the character herein described having an integral tab cut from the body of the paper board it is not practicable to produce a hinged portion by means of a continuous crease or groove for the reason that the crease must be near enough to the margin, or so far from the center that it would intersect the tab. If the crease were on the under side it would weaken the thin portion of the body of the cap below the tab and if on the upper side it would weaken the tab and destroy its efficiency.

In carrying out the present invention the disk is creased or grooved, preferably on its under surface, on lines extending from the tab or from near the tab to the margin of the disk, as will be explained more in detail in connection with the accompanying drawing in which:

Fig. 1 is a top plan view of a cap embodying the invention;

Fig. 2 is a bottom plan view of the same;

Fig. 3 is a section on the line 3-3 of Figure 1; and

Fig. 4 is a section of the mouth of a bottle provided with one of the hinged caps, the hinged portion being shown in the open condition.

Referring to the drawing 10 indicates the

cap, which is made or stamped from thin 55 pasteboard or cardboard and usually paraffined to make it waterproof. A tab 11 is formed by cutting part way through the paper disk on a somewhat semi-circular line and raising the cut portion in the course of 60 manufacture, the tab being then pressed back into position ready to be raised again when it is desired to withdraw the cap from a bottle or to raise the hinged portion of 65 the cap. This method of forming a tab is 70 illustrated in Patent No. 934,832 to Charles C. Parker. The hinged portion of the tab is preferably strengthened by means of a wire loop or staple 12, as described in Patent No. 1,402,454 to W. L. Smith. 75

In order to permit of raising a segment of the cap without disturbing the main portion in its seat in the neck of a bottle, the cap is weakened from its margin inward along two lines 13-13 preferably by pressing a groove into the body of the cap as indicated at 14, Figure 3. The grooves are preferably formed on the under side of the cap so as not to interfere with the printed matter on the upper surface. Furthermore 80 a groove on the under surface forms a better hinge to permit the smaller segment 10* of the cap being raised without raising the body of the cap from its seat in the neck of 85 the bottle. The grooves or lines of weakness 90 13 are, as shown, in alignment and they extend preferably from the margin of the cap to, or close to, the tab 11. If continued entirely across the cap on the under side the 95 grooves would render the thin portion of the cap under tab weak and might cause it to break or leak. If continued across the upper portion of the cap the tab might be severed or might break away when it is pulled. For these reasons the two grooves described 100 are provided and they are preferably formed on the underside of the cap and they are preferably so close to the margin that if connected they would intersect the outline of the tab. It will be noted that the thin portion of the cap under the tab and the two crease lines cooperate to form a hinge line across the cap.

Having thus described the invention what is claimed as new and desired to be secured by Letters Patent is:

A bottle cap consisting in a paper board disk having on its upper surface a lifting

tab which is formed of an integral portion of the disk, that part of the disk beneath the tab being thinner than the remainder of the disk, the tab being separated from the disk excepting at its outer edge and said cap being creased between the tab and its margin on alined lines substantially parallel

to the outer connected edge of the tab, said thin portion of the tab and said creases co-operating to form a hinge line across the 10 cap, for the purpose set forth.

In testimony whereof I hereunto affix my signature.

WALTER L. CHAPLIN.
